(57) **CLAIM**

The ornamental design for a toothbrush, as shown and described.

DESCRIPTION

FIG. 1 is a perspective view of a first embodiment of a toothbrush showing the handle of the toothbrush in phantom;

FIG. 2 is an enlarged fragmentary view taken from FIG. 1;

FIG. 3 is a front elevation view of the toothbrush;

FIG. 4 is a top plan view of the toothbrush;

FIG. 5 is a rear elevation view of the toothbrush;

FIG. 6 is a bottom plan view of the toothbrush;

FIG. 7 is a right side elevation view of the toothbrush;

FIG. 8 is a left side elevation view of the toothbrush;

FIG. 9 is a perspective view of a second embodiment of a toothbrush showing the handle of the toothbrush in phantom;

FIG. 10 is an enlarged fragmentary view taken from FIG. 9;

FIG. 11 is a front elevation view of the toothbrush illustrated in FIG. 9;

FIG. 12 is a top plan view of the toothbrush illustrated in FIG. 9;

FIG. 13 is a rear elevation view of the toothbrush illustrated in FIG. 9;

FIG. 14 is a bottom plan view of the toothbrush illustrated in FIG. 9;

FIG. 15 is a right side elevation view of the toothbrush illustrated in FIG. 9; and

FIG. 16 is a left side elevation view of the toothbrush illustrated in FIG. 9.

FIG. 17 is a perspective view of a third embodiment of the toothbrush showing the handle of the toothbrush in phantom;

FIG. 18 is an enlarged fragmentary view taken from FIG. 17;

FIG. 19 is a front elevation view of the toothbrush illustrated in FIG. 17;

FIG. 20 is a top plan view of the toothbrush illustrated in FIG. 17;

FIG. 21 is a rear elevation view of the toothbrush illustrated in FIG. 17;

FIG. 22 is a bottom plan view of the toothbrush illustrated in FIG. 17;

FIG. 23 is a right side elevation view of the toothbrush illustrated in FIG. 17; and

FIG. 24 is a left side elevation view of the toothbrush illustrated in FIG. 17.

(Continued)

FIG. 25 is a perspective view of a fourth embodiment of the toothbrush showing the handle of the toothbrush in phantom.

FIG. 26 is an enlarged fragmentary view taken from FIG. 25; FIG. 27 is a front elevation view of the toothbrush illustrated in FIG. 25;

FIG. 28 is a top plan view of the toothbrush illustrated in FIG. 25;

FIG. 29 is a rear elevation view of the toothbrush illustrated in FIG. 25;

FIG. 30 is a bottom plan view of the toothbrush illustrated in FIG. 25;

FIG. 31 is a right side elevation view of the toothbrush illustrated in FIG. 25; and,

FIG. 32 is a left side elevation view of the toothbrush illustrated in FIG. 25.

The elements shown in phantom form no part of the claimed design.

1 Claim, 28 Drawing Sheets
